United States Patent Office

Des. 208,980
Patented Oct. 24, 1967

208,980

GRAPHICAL DATA DIGITIZER

John A. Dykmans, Saratoga, and John Connor, Fairfax,
Calif., assignors to Calma Company, a corporation of
California

Filed Feb. 25, 1966, Ser. No. 1,197

Term of patent 14 years

(Cl. D26—5)

FIG. 1.

FIG. 2.

FIG. 3.

FIG. 4.

FIG. 1 is a perspective of a graphical data digitizer embodying our new design;

FIG. 2 is an elevation view taken from the right side thereof;

FIG. 3 is a rear elevation view thereof; and

FIG. 4 is an elevation view taken from the left side thereof.

The dominant features of our design reside in the portions shown in full lines.

We claim:

The ornamental design for a graphical data digitizer, substantially as shown and described.
